UNITED STATES PATENT OFFICE.

ALEXANDER CRAIG, OF LONDON, ENGLAND.

DEVICE FOR WAVING AND CURLING HAIR.

Application filed December 3, 1927, Serial No. 237,553, and in Great Britain May 6, 1927.

This invention relates to devices for waving and curling hair and has for its principal object to provide means by which the hair can be wound on to a curling rod or the like of any suitable description and simultaneously subjected to pressure or compression, and without tensioning or stretching the hair.

It has for a further object to provide winding means to coil the hair on to the rod, the winding means having combined therewith heating means of any desired type, so that the hair whilst being coiled on the rod is subjected to heat as well as to pressure or compression.

15 A further object is to maintain the coiled hair, under pressure or compression, whilst being treated, and a still further object is to coil the hair in flat somewhat rectangular section helices, the longer dimension of the rectangle being at right angles to the axis.

Another object is to combine with the curling rod two pressure plates, one normally fixed at the end of the rod but from which it is preferably detachable, and the other mounted around the rod and adapted to slide in tight frictional engagement therewith or with the surrounding winder casing. Still another object is to cause the hair whilst being wound to enter between the pressure plates to produce the flat rectangular section coils and to force the frictionally mounted plate away from the other plate, thus subjecting the hair to pressure upon entering between the plates and maintaining the hair under pressure whilst subjected to treatment between the pressure plates, by heat with or without suitable compounds.

In order that the invention may be better understood, it will now be described with reference to the accompanying drawing in which:—

Fig. 1 is a somewhat diagrammatic elevation of one form of rod, winder, and winding means constructed according to the invention.

Fig. 2 is an exterior elevation of the curler and winder combined, shown to a larger scale.

Fig. 3 shows a similar view to Fig. 2 with parts in section.

50 Fig. 4 is an under plan of Fig. 2.

Fig. 5 is a sectional plan taken from below on the line 5—5 Fig. 3.

Fig. 6 is a section on the line 6—6, Fig. 3.

Fig. 7 shows a side elevation of the movable

or upper pressure plate, drawn to a larger 55 scale.

Fig. 8 also shows to the same scale the frictional gripping member which carries the pressure plate shown in Fig. 7 and co-operates with the interior of the winder.

Fig. 9 is an under plan of Fig. 8.

Fig. 10 is an under plan of Fig. 7.

Fig. 11 is a fragmentary elevation, partly in section, of the lower portion of the combined winder and rod illustrating the method 65 of coiling the hair, and

Fig. 12 shows a diagrammatic view, to a larger scale, illustrating the coils of the hair as wound on the curler made according to the invention, the separate coils being drawn 70 apart to show their formation.

In the drawings, the winder comprises an outer cylindrical casing 14 with a longitudinal slot 15, and a smaller inner cylindrical casing 16 also formed with a longitudinal slot. 75 The casings 14 and 16 are coaxial and the slots come in the same radial position, the edges thereof being joined together at 17. The lower end of the combined casing is closed at 18 and the upper end is left open. The 80 space between the inner and outer cylindrical casings 16 and 14 forms a receptacle for a shaped electrical heating element 19. At the upper end the casings 14 and 16 are carried by a collar 20 of insulating material having pins 21 projecting therefrom, the said pins being in electrical connection with the windings of the heater 19. 22 is a connecting member of insulating material which has mounted therein a ring member 23 of insulating material which is adapted to rotate in the connecting member 22. The ring member 23 has grooves on its exterior in which are mounted contact making members in connection with the leads of a cable 24. One of these 85 contact members makes electrical connection with one of the pins 21 and the other with the other pin so that when the ring 23 rotates in the connector 22 the pins 21 are always in electrical connection with the connections from the leads 24. 25 is an enlarged boss mounted 100 loosely in the inner casing of the winder, which boss is furnished with a notch 26 at the upper side. The inner casing of the winder has connected thereto a sleeve member 27 105 which passes right through the ring 23 and connector 22 and serves to secure the whole winder in a rotatable manner to the connec-

- tor 22. It is retained in position by means of a collar 28.
- The upper end of the sleeve member 27 is notched at 29 and is adapted to cooperate with any suitable winding device which may be hand or power operated. For example the winding device shown in Fig. 1 may be employed. This comprises two levers 30 and 31 having turned round ends 32 and 33. The turned round end 32 is formed with a bearing 34 for one end of a shaft or spindle 35. This shaft or spindle 35 has keyed thereon a ratchet wheel 36 and mounted loosely between the bearing 34 and ratchet wheel 36 is a toothed wheel 37. The turned round member 33 on the underside is formed with a rack, the teeth of which engage with the teeth of the wheel 37. The arm 30 at the other end is provided with another bearing 38 for the shaft 35 and to this bearing the arm 31 is pivoted at 39 as shown. Spring means, not shown on the drawing, is incorporated between the arms 30 and 31, for example at the hinge, tending to keep the arms drawn apart, in which position they are maintained normally by means of a stop, at the hinge or between the arms. This position is shown at Fig. 1. When the arms 30 and 31 are gripped together the teeth of the rack on the member 33 cause the wheel 37 to be turned. This wheel 37 carries a pawl 40 engaging with the ratchet wheel 36. The return movement is effected by the spring between the arms 30 and 31. Either on the forward movement or on the return movement, according to circumstances, the pawl 40 engages the ratchet wheel 36 and drives the shaft 35. In this opposite direction the pawl 40 slips teeth in the usual manner.
- 40 A casing 41 is attached to the bearing 38 and into this casing the shaft 35 projects and has mounted thereon a bevel wheel 42, which meshes with another bevel wheel 43 carrying on the exterior a sleeve 44 with a projection or projections 45. This sleeve rotates over a fixed projecting stem 46 fixed to the interior of the casing 41 so as not to rotate. The stem 46 at the front end is formed with a projection or engaging member 47.
- 45 In use the sleeve 44 fits within the notched end of the sleeve 27 so that the pin 45 engages in the notch or notches 29. In this position also the projection 47 comes into the slot or notch 26 in the boss 25. The boss 25 has formed therewith or attached thereto a rod 48 which is actually the rod of the curler.
- 50 This rod 48 is located as shown centrally in the interior of the casing 16 and projects therefrom to a slight extent. At its lower end it is formed with a notch 49 in the side thereof and on this lower end is mounted a device comprising a combined pressure plate and means for holding the strand of hair in a temporary manner prior to and during the first portion of the winding. This combined

device comprises an upper plate 50 having an aperture therein of sufficient size to enable it to pass up over the end of the rod 48. On the upper side this plate is formed with a concentric depression or groove 51 (see Fig. 3) into which the end of the curler casing fits as shown. This plate is also provided with a notch 52 (see Fig. 4). The under member comprises another plate 53 pivoted at 54 to the plate 50 and having a quadrant or arc-like portion 55. The radius of this quadrant or arc-like portion 55 is such that the plate 53 by being turned on the pivot 54 can be brought to engage in the notch or slot 49 in the end of the rod 48 to hold the combined device comprised by the plates 50 and 53 in position on the end of the rod. The plate 53 is moved by means of a handle 56, and taken at the position shown in Fig. 4, if the handle 56 is depressed to a sufficient extent, the plate 50 will be freed from the notch 49 enabling the whole device to be detached from the rod 48. To again attach the device it is simply necessary to pass the plate 50 over the end of the rod 48 and then to turn the plate 53 to bring the portion 55 into engagement with the notch 49; this secures the device in position.

The plate 50 also is formed with a projecting portion 57 so disposed that when the quadrant or arc-like portion 55 engages the notch 49, it comes over the notch 52 so that the flat end 58 of the portion 53 approaches the end of this notch. Between this flat end 58 and the end of the notch 52 the strand of hair is adapted temporarily to be held during the first portion of the winding operation the strand of hair being brought into position into the notch prior to the complete movement of the plate 53.

A clutch or friction member is mounted to slide on the rod 48 and comprises a sleeve 59 with a bore therethrough of sufficient size to move easily on the rod 48. This sleeve is enlarged in an intermediate position, and the enlargement formed with a groove 60. Around this grooved portion is located a helical spring 61, the ends 62 of which project as shown in Fig. 8. The parts are of such diameter that the exterior of the spring 61 when free to expand comes into tight gripping contact with the interior surface of the inner casing 16 or the sleeve carried thereby. When, however, the ends 62 are brought together, the effective diameter of the turns of the spring is lessened and these then come out of gripping contact with the interior surface. The ends 62 of the spring 61 project through the slot 15 and have mounted thereon a controlling member 63. The turned round ends of the spring pass into a long slot 64 on the underside of this controlling member and project over the edges thereof. The controlling member, as will be seen, is formed by a short length of flattened tube and when rotated from the position shown in Fig. 2,

through a right angle, it will be understood that the ends 62 of the spring are brought closely together owing to the cam-like action of the slot 64 and the spring is brought out of gripping contact with the inner sleeve. When the member 63 is turned in the opposite direction, or allowed to turn in this direction, owing to the expansive action of the spring, the turns thereof again come into gripping contact with the inner casing. On to the reduced end 65 of the sliding member 59 is adapted to be mounted a moving pressure plate 66 which is held in position by a pin 67 on the member 59 engaging in a corresponding aperture 68 in the plate. The shape of the plate is shown in Fig. 10 and as will be seen this plate comprises a strip-like member 69 which partly envelops and is attached to the plate and which at the free extension comprises a tongue 70. This tongue 70 projects as shown through the slot 15 and forms a guiding member for the strand of hair. Where the member 69 meets the plate 66 the plate is formed with a bevel 71 as shown in Fig. 10. The plate 66 is made detachable as shown so that if desired it can be placed on the reduced end 65 from either end, so as to cause the tongue 70 to project from the slot 15 in either direction, according to the direction of winding. By manipulating the member 63 the spring 61 can be brought out of gripping engagement and the whole device comprising the member 59 and plate 66 can be slid on the rod 48 and within the casing. It can for example be brought into close proximity with the plate 50 and this is the position ready for curling the hair on the rod.

The operation is as follows: Rotation is effected by manipulating the handles 30 and 31 as previously explained and this causes the sleeve 27 with the winder parts attached thereto as previously explained to be rotated in the connector 22 which does not rotate, so that the whole winder rotates around the rod 48 which is held fixed by the projection 47 engaging with the notch 26; at the lower end it will be appreciated that the projecting portion of the winder rotates in the concentric groove 51. Owing to the frictional connection of the spring 61 the member 59 and upper pressure plate 66 are rotated with the winder and it is pointed out that to move the upper pressure plate 66 along the rod 48 and within the casing, it is necessary to exert a good deal of pressure on the underside of the plate 66 to overcome the frictional gripping of the spring 61 on the interior of the casing. The strand of hair is engaged in the notch 52 as previously explained and temporarily held by the base 58 and then the strand of hair is placed between the tongue 70 and the casing and winding commenced. The hair is carried round by the tongue and the relative movement causes it to be spread out and pulled between the two plates 50 and 66, the bevel 71 facilitating the

entry of the hair between these plates. Owing to the resistance to longitudinal movement of the plate 66 the hair is subjected to pressure and is spread out into a flat strand similar to that illustrated in Fig. 12 but with the turns touching each other. By continued winding the whole of the strand of hair or the like, or that portion it is desired should be treated, is brought between the two pressure plates, and in this action the upper pressure plate 66 is forced along the rod 48 against the frictional grip of the spring. Consequently, during the whole of the winding operation the hair being wound is subjected to pressure and compression, and moreover this pressure or compression is maintained during the whole of the subsequent treatment, and may be increased by forcing the top plate downwards by hand.

While the hair is being wound, the electric heater inside the winding portion is preferably in operation and consequently the hair is subjected to heat treatment while it is being wound and as a consequence the swelling occasioned by this preliminary heating increases the pressure or compression. Moreover the pressure or compression acts upon the hair while in the swollen condition.

Fig. 11 shows a number of turns of the coiling illustrating how these are subjected to pressure between the two plates. A portion of the figure shows the method by which the strand of hair passes between the tongue 70 and the casing and is turned under by the bevel 71 to come beneath the pressure plate 66 and to be spread above the last made coil of the helix.

Any suitable means may be provided for rotating the winder around the non-rotatable rod and in some cases this may take the form of a flexible or other shaft driven from a pedal or by power means, preferably under control. This flexible or other shaft would be provided with a suitable coupling means enabling it to be put into operative connection with the winding device in a simple manner and as simply detached ready to be coupled to another winder.

For reverse winding a suitable reversing gear could be incorporated in the drive. As shown on the drawings, this reverse is effected by uncoupling the tool comprising the levers 20 and 31 from the winder and placing the end lettered 72 into engagement with the sleeve 27 and notch 29. The end lettered 72 on the drawing comprising an exterior casing or cap which is adapted to be removed exposing a structure similar to that at the other end, that is to say a sleeve 44 and projection 47. When thus used the cap can be placed at the end, out of use.

After the first coil or coils have been wound upon the rod, it is no longer essential to hold the hair between the face 58 of the plate 53 and the end of the notch 52 and consequently

- the operator need not cause pressure to be exerted thereon, but the pressure between the coils holds the parts in position. Similarly at the end of the winding it is not necessary 5 as at present to tie or otherwise secure the end or other portion of the strand of hair being treated to the rod as the pressure by which it is held between the pressure plates secures the finished coil in position.
- 10 In place of the spring means gripping the interior of the winding casing, in some cases the spring may grip around the rod, and with this construction, after the winding has been effected, the winder may be entirely removed 15 from the curler leaving the hair coiled on the curler rod and held between the two pressure plates. With this construction, other heating means may then be placed around the hair coiled on the rod if so desired.
- 15 The curler rod may be a simple solid rod, for example as shown on the drawings, or a hollow rod or a compound rod comprising an inner member which may be hollow or solid 20 and an outer sleeve-like member.
- 20 The hair coiled on the rod may be impregnated with any desired liquid or compound, or may be moistened by water. This treatment by liquid or compound may be applied 25 periodically during the whole of the heating treatment. In addition the coiled hair can be treated with oil of any kind or other neutralizing agent whilst the winding means is in position and while the hair is under heat.
- 30 35 The slot in the winder serves to enable the heat to be dissipated, thus preventing over-heating, and also enables the hair held pressed on the rod to be partly exposed so that moisture, compound or oil can be applied thereto 40 while it is under treatment.
- 35 The winder may be made in one more parts hinged or otherwise attached together and adapted to be moved apart or closed together enabling them to encircle the rod or the like, 45 and in all preferred forms comprise a hollow chamber or chambers for the reception of the heating medium. This heating medium may be steam or hot water or other liquid, and the chamber or chambers of the winder may 50 be included in a circulation for such fluid. In other cases however the hollow chamber or chambers have an electric heating element or elements as described, the element or elements being included in a desired circuit or 55 circuits.
- 60 In some cases the warm or other winder may be held from rotation and a part of the rod or the like may be rotated within the warm winder, the effect being precisely the same as that previously described.
- 65 In addition to the warm or other winder rotating relatively to the rod or the like upon which the hair is to be coiled, in some cases a means for carrying a chemical or compound preferably in the form of a shaped sachet

may be employed. This chemical is thus ready for use when the strand of hair has been coiled on the rod to a desired extent and can be rendered operative by the heat treatment, by the addition thereto of water or other liquid or by a combination of such means. The sachet may be shaped to fit into a suitable shaped chamber which may partly encircle the strand of hair and the interior chamber may have perforated, slotted or other walls facilitating access of the material to the hair.

70 By applying heat to the hair at the same time as it is coiled on the rod or the like and preferably subjected to pressure, it is pointed out that the hair swells immediately and becomes soft, thus enabling it readily to be coiled and bringing it in a condition responsive to the coiling and pressure treatment, and set up initial pressure by the swelling. 80 During the continuance of the heating the hair dries and contracts and thus readily absorbs the treating liquid or compound and is ready to take a permanent set.

75 85 90 95 In use, it will be realized that the winder and compression producing rod on which the strand of hair is coiled may be employed for treating strands of hair which have not been already subjected to permanent waving treatment, and in this case the whole of the strand extending from scalp to the free end may be wound on the rod. In other cases where the strand of hair has been permanently waved, and where since such permanent waving the hair has grown, the portion of the hair between the scalp and the end of the waved portion, which has not previously been treated, may with the device constructed according to the invention be treated, as when, in coiling the strand on the rod, at least that portion 100 of the strand commencing at the scalp, when the portion that has already been waved reaches the slot in the warm winder, no further portion of the strand is wound upon the rod. The portion of the strand already 105 on the rod is treated and the portion of the strand left out does not come to any harm or is not injured in any way as the temperature is low and consequently this projecting portion of the strand is not liable to become 110 damaged or burnt.

115 120 125 In some cases in place of the device illustrated for holding the lower pressure plate in position, other means may be adopted, for example the rod on which the hair is coiled may be made in the manner of a split pin and have a small eye at the lower end adapted to take a pin for preventing the removal of the pressure plate threaded on to the end of the rod. Again, other means than that illustrated may be used, in some cases, for holding the strand of hair temporarily during the first portion of the winding.

130 The invention is not limited to the various constructional embodiments or modifications

described as many variations may be made coming within the scope of the claims.

What I claim and desire to secure by Letters Patent of the United States of America

5 is:—

1. Devices for waving and curling hair comprising a rod on which the hair is adapted to be coiled, means on the rod against which one end of the coil of hair on the rod is adapted to take, other means on the rod adapted to take against the other end of the said coil of hair, and means for causing the two last mentioned means to subject the coil of hair on the rod to pressure in a direction parallel to the 15 axis of the rod, for the purposes set forth.

2. Devices for waving and curling hair comprising a rod, a pressure plate detachably secured to one end of the rod, and another pressure plate adapted to move axially on the 20 rod against a suitable resisting medium in order to hold the hair coiled on the rod between the two plates under pressure.

3. Devices for waving and curling hair comprising a rod, a pressure plate detachably secured to one end of the rod, means associated with the said pressure plate to hold a strand of hair during the preliminary winding on the rod, and another pressure plate adapted to move axially on the rod against a suitable 25 resisting medium in order to hold the hair coiled on the rod between the two plates under pressure.

4. Devices for waving and curling hair comprising a rod, a pressure plate detachably secured to one end of the rod, means associated with the said pressure plate to hold a strand of hair during the preliminary winding on the rod, another pressure plate adapted to move axially on the rod, and spring 30 means associated with the second mentioned pressure plate and adapted to grip with a tight frictional grip the rod, in order to hold the hair coiled on the rod between the two plates under pressure, and to move against the frictional grip by the coiling of the hair 35 on the rod.

5. Devices for waving and curling hair comprising a rod, a pressure plate detachably secured to one end of the rod, another pressure plate adapted to move axially on the rod against a suitable resisting medium, a winder associated with the rod and adapted to encircle it to a desired extent, and means for rotating the said winder with respect to the 40 rod, all for the purposes set forth.

6. Devices for waving and curling hair comprising a rod, a pressure plate detachably secured to one end of the rod, another pressure plate adapted to move axially on the 45 rod against a suitable resisting medium, a winder associated with the rod and adapted to encircle it to a desired extent, means for rotating the said winder with respect to the rod, and heating means associated with the 50 winder, all for the purposes set forth.

7. Devices for waving and curling hair comprising a rod, a pressure plate detachably secured to one end of the rod, another pressure plate adapted to move axially on the rod against a suitable resisting medium, a winder 55 comprising a hollow body associated with the rod and adapted to encircle it to a desired extent, heating means located in the hollow body of the winder, and means for rotating the winder with respect to the rod, all for the purposes set forth.

8. Devices for waving and curling hair comprising a rod, a pressure plate detachably secured to one end of the rod, another pressure plate adapted to move axially on the 60 rod, against a suitable resisting medium, a winder comprising a hollow body associated with the rod and adapted to encircle it to a desired extent, an electrical heating element located in the hollow body of the winder, and means for rotating the winder with respect to the rod all for the purposes set forth.

9. Devices for waving and curling hair comprising a rod, a pressure plate detachably secured to one end of the rod, another pressure plate adapted to move axially on the rod against a suitable resisting medium, a winder associated with the rod and adapted to encircle it to a desired extent, means for rotating the winder with respect to the rod, heating means associated with the winder, and a slot extending along the side of the winder, 70 all for the purposes set forth.

10. Devices for waving and curling hair comprising a rod, a pressure plate detachably secured to one end of the rod, another pressure plate adapted to move axially on the rod, a winder formed by a sleeve associated with the rod and adapted to encircle it to a desired extent, spring means associated with the 75 second mentioned pressure plate adapted to come into frictional gripping contact with the interior of the winder sleeve, means for rotating the winder with respect to the rod, and heating means associated with the 80 winder, all for the purposes set forth.

11. Devices for waving and curling hair comprising a rod, a pressure plate detachably secured to one end of the rod, another pressure plate adapted to move axially on the rod, a winder formed by a sleeve associated with the rod and adapted to encircle it to a desired extent, spring means associated with the second mentioned pressure plate adapted to come into frictional gripping contact with the interior of the winder sleeve, means for 85 releasing the frictional grip of the sleeve, means for rotating the winder upon and with respect to the rod, and heating means associated with the winder, all for the purposes set forth.

12. Devices for waving and curling hair comprising a rod, a pressure plate detachably secured to one end of the rod, a circular groove or recess on the inner surface of the 90

- plate concentric with the rod, another pressure plate adapted to move axially on the rod, a winder formed by a sleeve associated with the rod and adapted to encircle it to a desired extent so that the lower end of the sleeve enters the circular groove in the first mentioned pressure plate, spring means associated with the second mentioned pressure plate adapted to come into frictional gripping contact with the interior of the winder sleeve, means for rotating the winder sleeve with respect to the rod, and heating means associated with the winder, all for the purposes set forth.
13. Devices for waving and curling hair comprising a rod, a pressure plate detachably secured to one end of the rod, another pressure plate adapted to move axially on the rod against a suitable resisting medium, a sleeve-like winder associated with the rod and adapted to encircle it to a desired extent, means for rotating the winder with respect to the rod, heating means associated with the winder, a slot extending along the

side of the winder, and a hook-like tongue attached to the second mentioned pressure plate adapted to project through the slot in the winder to form a guide for the strand of hair, all for the purposes set forth.

14. Devices for waving and curling hair comprising a rod, a pressure plate detachably secured to one end of the rod, another pressure plate adapted to move axially on the rod against a suitable resisting medium, a winder associated with the rod and adapted to encircle it to a desired extent, means for rotating the winder with respect to the rod, heating means associated with the winder, a slot extending along the side of the winder, a hook-like tongue attached to the second mentioned pressure plate adapted to extend through the slot in the winder to form a guide for the strand of hair, and a bevel on the underside of the second mentioned pressure plate adjacent its junction with the tongue, all for the purposes set forth.

In witness whereof I affix my signature.
ALEXANDER CRAIG.
